Fig.8

Fig.9 Fig.10

Fig.11

FIGURE 1 is a perspective view of a first embodiment of my windscreens wiper, seen from one side and one end;

FIGURE 2 is a plan view of said first embodiment;

FIGURE 3 is a view from the left end of FIG. 1;

FIGURE 4 is a perspective view from one end and one side of a second embodiment of my windscreens wiper;

FIGURE 5 is a view of the wiper from the other side;

FIGURE 6 is a plan view of the wiper;

FIGURE 7 is a view from the left end of FIG. 4;

FIGURE 8 is a perspective view from one end and one side of a third embodiment of my windscreens wiper;

FIGURE 9 is a view of the wiper from the other side;

FIGURE 10 is a plan view of the wiper; and

FIGURE 11 is a view from the left end of FIG. 8.

This application is a continuation-in-part of my prior application Ser. No. D. 3,902, filed July 5, 1966, which is a continuation of applications Ser. No. D. 86,679, filed Aug. 23, 1965, and Ser. No. D. 87,362, filed Oct. 7, 1965, all now abandoned.

I claim:

The ornamental design for a windscreens wiper, as shown.
